UNITED STATES PATENT OFFICE.

WILLIAM F. BOSTOCK, OF SOUTH BRAINTREE, MASSACHUSETTS.

ORNAMENTED SHOE UPPER.

Application filed December 17, 1923. Serial No. 681,138.

To all whom it may concern:

Be it known that I, WILLIAM F. BOSTOCK, a citizen of the United States, residing at South Braintree, in the county of Norfolk 5 and State of Massachusetts, have invented new and useful Improvements in Ornamented Shoe Uppers, of which the following is a specification.

The present invention relates to shoe making generally and particularly to ornamented shoe uppers of the type shown in my patent application filed December 2nd, 1921, Serial No. 519,378, and entitled Ornamented shoe upper.

The general object of the present invention is the same as that set forth in my previous application, that is to get ornamental effects which are not obtainable by the use of materials previously employed in shoe making; effects which are superior to those previously obtained by reason both of their greater brilliancy, and their greater durability and less liability of being soiled or defaced. The new step of the present invention, as compared with that set forth in my prior application, consists in the application to, or combination with, a shoe upper, of a string or strand of beads or the like, extending along the edge of the shoe upper, or of one of the pieces composing the upper, and secured by means, which is also preferably ornamental, like or equivalent to the ornamental edging material described in my prior application.

Referring to the drawings in which I have shown one of the embodiments of my present invention Figure 1 is a plan view of the fore part of the shoe to which ornamentation of the sort above described in general terms has been applied.

Figure 2 is a cross section on a much enlarged scale taken on the line 2—2 of Figure 1.

Figure 3 is an enlarged detail view of the ornamental edging material shown in Figure 1.

Figure 4 is a sectional view similar to Figure 2 showing a modification of the invention.

Like reference characters designate the

same parts wherever they occur in all of the figures.

The letter *a* in Figures 1, 2 and 4 represents the vamp of a shoe upper and *b* represents an ornamental leather strap which is applied to the vamp adjacent to the throat thereof. This strap is stitched to the outer side of the vamp and is in effect a part thereof. It exemplifies one member or part of a shoe upper which is stitched to another member or part of the upper in such manner that at least one edge overlaps the second named part and is exposed on the outer surface of such other part. The exposed and overlapping edge *c* (shown in Figure 2) of the strap *b* is the part of the upper to which the ornamental edging forming the substance of this invention is applied.

The edging referred to comprises a string of beads *d*, which may be strung on any suitable filament, such as a wire, a thread or strand of vegetable fibres, or a strand of animal hair or fibre, or other material. For the purpose of this specification, the term "string of beads" is intended to include a series of beads or similar bodies arranged and connected in a flexible line or string by any suitable means or construction, including those mentioned above. In other words the word "string" has no restrictive significance as to the material or size or other characteristics of the connectors by which the beads or the like are thus connected. In Figures 2, 3 and 4, the connector is represented as a flexible metallic wire *e*.

The beads or equivalent ornamental bodies thus arranged in a string *e* may be of glass, metal or any other material of which beads can be made, in any size and shape desired, and of any colors desired.

The bead string so characterized is attached to the exposed edge *c* of the part *d*, by clips or straps or loops, such as those shown at *f* in Figures 1, 2 and 3 and at *f* in Figure 4.

The clips *f* shown in Figures 1, 2 and 3 are of metal doubled on a curve wide enough to enclose the strand on which the beads are strung, and also to permit the edges or lips of the clips to embrace the edge of the piece

b, but preferably not wide enough to admit the beads. The clips are placed over the exposed edge of the piece *b* and are clamped thereon by pressure. If desired, the under 5 part of the clip may be offset at one or more points as shown at *g* in order to indent the leather piece *b*, so as to increase the security of gripping the same, and also the extreme edge of the outer part of the clip may be 10 turned inward so as to bite into the outer surface of the leather piece, in order to still further increase the security of the grip. However these last mentioned aids to obtain a secure grip may be dispensed with and 15 friction alone depended upon to hold the clips, after they have been compressed under sufficient pressure around the exposed edge of the leather piece.

Clips or loops of other materials than 20 metals may be used for the same purpose, as for instance celluloid, rubber, or other compositions capable of being molded or rolled into sheet form and of being molded or bent into the shape of the clips here shown, and 25 compressed on the edge of a leather piece, with heat or not, according to the nature of the material. Such a non-metallic clip, and specifically one made of celluloid is shown at *f*¹ in Figure 4. For clips of such non- 30 metallic materials, since they may not have great enough inherent stiffness to be securely held by their grip on the leather, I have provided an additional lock which consists in perforating the leather piece in that part 35 which is overlapped by the sides of the clip, and filling the perforations with a mass *h* of cement or other more or less suitable plastic material which will adhere or combine with the material of the clip, and will 40 become hard and firm by drying or other action within a reasonably short time after being applied.

The clips thus described, if of metal, may 45 have the natural color of any selected metal as gold, silver, steel, etc., or any other color to which metal may be changed by oxidation or other chemical treatment, or the clips may be covered with enamel of any color. So also the non-metallic clips may be colored 50 in the course of making the compound in any desired color. Either sort of clip may also serve as a setting for a stone or jewel *i*, which being confined between the leather piece and the outer side of the clip, as 55 shown in Figure 2, is exposed to view through a hole in the clip. Thus not only the beads, which are held by clips close to the edge of the leather, offer wide possibilities for beautiful and striking effects of ornamentation of color and form, but the clips themselves offer additional possibilities of contrasting or enhanced ornamental effects due to the colors which may be given to them, as above described, to the form or 60 outline to which the exposed sides of the

clips may be cut, and to the jewels which may be set in the clips.

While clips of the sort above described, having both the mechanical function of securing the bead string to the upper and also the aesthetic function of ornamentation, are the preferred means for attaching the beads and are claimed as such; nevertheless I do not limit my claim to protection exclusively to the combination of a 70 bead string with such attaching clips, but claim also the application of a string of beads to a shoe upper in substantially the manner disclosed in this specification, by 75 whatever means it may be secured. 80

While I have described the ornamentation as applied to a specific part of the shoe upper, that is to a binding or edging strip along the throat of the vamp, it is to be understood that this showing is for illustration only, and is intended to typify any parts of the upper to which such ornamentation may be applied. For example, in other styles of shoes, there may be a toe cap having an exposed edge across the fore part of 85 the vamp, or the vamp may be made of a number of pieces stitched together with one piece overlapping another. A bead string may be applied according to this invention to such overlapping edge of any of these 90 parts or even to the extreme edge of the upper, such as the edge *j* at the throat of the vamp, the upper edge *k* of the quarter, or either or both edges of an instep strap *l* or similar part of the upper. In short my invention contemplates the application of a 95 bead string substantially as shown to any exposed edge or any part of a shoe where it extends around or over a part of the foot on which the shoe is worn. 100 105

I claim:

1. A shoe upper comprising a number of pieces stitched together, and a string of beads attached to, and extending along, an exposed edge of said upper. 110

2. A shoe upper comprising a number of pieces stitched together in overlapping relationship, and a string of beads attached to the exposed overlapping edge of one of said pieces and extending along such edge. 115

3. A shoe upper comprising a number of pieces stitched together in overlapping relationship, a string of beads extending along an exposed edge of a part of the upper, and clips embracing said string and the said 120 edge, and being secured to the upper close to said edge.

4. A shoe upper comprising a number of pieces stitched together in overlapping relationship, a string of beads extending along- 125 side the exposed overlapping edge of one of said pieces, and clips embracing said string and the adjacent edge portion of the said piece and secured to the latter.

5. A shoe upper comprising a number of 130

pieces stitched together in overlapping relationship, clips folded to embrace an exposed edge of the upper and being secured thereon to form loops at such edge, and a string of beads passing through said loops and extending beside such edge.

6. A shoe upper and a clip applied to an edge thereto and formed with lips or wings

which embrace such edge, and a jewel confined between said upper and the outer wing ¹⁰ of said clip and protruding into a hole in such wing.

In testimony whereof I have affixed my signature.

WILLIAM F. BOSTOCK.
